UNITED STATES PATENT OFFICE

BERT DAVID FEILD, OF LONDON, AND THEODORE CECIL STANDBROOK, OF ILFORD, ENGLAND, ASSIGNORS TO STANFIELD RADIO COMPANY, LIMITED, OF LONDON, ENGLAND

POTENTIAL SUPPLY MEANS

Application filed January 10, 1929, Serial No. 331,416, and in Great Britain December 23, 1927.

An application for this invention has been filed in Great Britain December 23, 1927.

This invention relates to potential supply means suitable for use in wireless receiving apparatus.

- 5 More particularly the invention relates to apparatus for producing substantially non-fluctuating unidirectional potentials suitable for use for supplying operating potentials to 10 thermionic valves and like discharge devices, and comprising a transformer whose primary winding is arranged to be supplied from a relatively low potential direct current source through the contacts of a vibratory inter-
rupter actuated by the leakage field of the 15 said transformer, and whose secondary winding is associated with a rectifier having no moving parts (i. e. a static rectifier), and a smoothing element consisting of inductance 20 in series with and capacity in shunt with the load.

According to this invention the core of the transformer is provided with a saw cut or small transverse gap, and the vibratory interrupter is so mounted as to be attracted towards that limb of the core in which the said gap is provided.

The invention is illustrated in the accompanying drawing, which shows one convenient arrangement.

30 Referring to the drawing, 1 is a terminal adapted to be connected to the positive terminal of a low voltage battery, while 2 is a terminal adapted to be connected to the negative terminal thereof. 3 is the primary and 35 4 the secondary of a transformer embodied in apparatus of the kind referred to hereinbefore.

The core 5 of the transformer is cut 40 through at 6 in the limb adjacent a vibratory armature or interrupter 7 which is supported in position by means of a rubber hinge 8. 9 is the adjustable contact breaker associated with the armature 7; 10, 11 and 12 are fixed 45 condensers; 13 is a choke; 14, 15 the cathode

and anode respectively of a static rectifier constituted by a rectifying valve, and 16 and 17 the negative and positive output terminals respectively.

It will be seen that the low voltage battery 50 is employed to heat the cathode 14 of the rectifier, and the said cathode is connected through the choke 13 to the positive terminal 17. Since this terminal will in use be connected to the anode or anodes of the valve or valves to be supplied with energy, clearly the low tension battery cannot also be employed to energize the cathode or cathodes of the said valve or valves.

What we claim is:—

1. In combination, a transformer having a primary and a secondary winding, said primary winding carried by a core section provided with a narrow transverse air gap, a vibratory interrupter having its contacts 60 in series with said primary winding and having its operating armature located in the leakage field adjacent said air gap, a rectifying valve in series with said secondary winding, a source of low potential direct 65 current for supplying said primary winding and for heating the cathode of said valve and a smoothing device in the circuit of the secondary winding comprising an inductance in series with said secondary winding 70 and a capacity in shunt across the external 75 load circuit.

2. Apparatus for producing substantially non-fluctuating unidirectional potentials for supplying operating potentials to the thermionic valves of a wireless set, and comprising in combination a transformer having a core structure provided with a narrow air gap providing a leakage field and a primary and secondary winding, a vibratory interrupter having its contacts in series with said primary winding and having its operating armature located in the leakage field of the transformer, a rectifying valve in series with 80 said secondary winding, and means for sup- 85 90 94

plying from a single source low potential direct current to said primary winding and to the cathode of said rectifying valve and a smoothing device in the circuit of the secondary winding including an inductance in series with said secondary winding and a capacity in shunt across the external load circuit.

5 In testimony that we claim the foregoing as our invention, we have signed our names
10 this 21st day of December, 1928.

BERT DAVID FEILD.

THEODORE CECIL STANDBROOK.
